CLAIM

The ornamental design for a folding cleat, as shown and described.

DESCRIPTION

FIG. 1 is a perspective view of a folding cleat showing the claimed design;

FIG. 2 is a top plan view thereof;

FIG. 3 is a left side view thereof;

FIG. 4 is a front elevational view thereof;

FIG. 5 is a right side view thereof;

FIG. 6 is a rear elevational view thereof; and,

FIG. 7 is a bottom plan view thereof.

The broken lines in FIG. 7 depict portion of the folding cleat that form no part of the claimed design.
